UNITED STATES PATENT OFFICE.

CHARLES G. JANSKY, OF BERWYN, ILLINOIS.

ELECTRICAL CONNECTER.

Application filed October 18, 1926. Serial No. 142,171.

The present invention relates to electrical connecters which are non-corroding and fully insulated, and are of particular importance for use with storage batteries, but my invention is of general application and my connecters are capable of use with all types of electrical apparatus.

One of the objects of my invention is the provision of a non-corroding connector for storage batteries.

Another object of my invention is the provision of a non-corroding electrical connector of general application to electrical apparatus.

Another object of my invention is the provision of novel electrical connecting means enclosed in an insulating casing, and adequately insulated for handling while in use.

Another object of my invention is the provision of a novel method of making or constructing electrical connecters of the class described.

Other objects and advantages of my invention will appear more fully from the following description, taken in connection with the accompanying drawings, in which similar characters of reference indicate similar parts throughout the several views. In the drawings accompanying this description:

Figure 1 is a view in perspective of a modern B battery equipped with a connector according to my invention.

Figure 2 is an enlarged cross sectional view of the insulating frame and screw of my connector.

Figure 3 is an enlarged cross sectional view taken on a plane at right angles to the view of Figure 2, showing the complete assembly of my connector with a battery post.

Figure 4 is an elevational view showing the molding core in position to form the terminal plug.

Referring to Figure 1, 10 indicates the modern B battery having the usual container 11, closed by an insulating cap 12, having a plurality of projecting terminal posts 13 and 14 for connection to the external circuit.

The numeral 15 indicates my connector in its entirety, as shown in Figure 1, consisting of an insulating body 16, which may be shaped by cutting tools to the conformation shown in Figure 2, but which I prefer to construct by moulding the same of in-

sulation such as bakelite, or other insulation having similar properties.

The insulating body 16 is provided with a transverse opening 17, which may extend from one side into the said insulating body, if desired, but preferably extends through the same. The insulating body 16 is also provided with a threaded bore 18, extending from one end transversely to the bore 17, connecting therewith, and preferably extending past the same to form a threaded pocket 19 on the opposite side of the bore 17. The bore 18 is provided with a threaded insulating screw 20, which may also be made by the use of cutting tools, but I prefer to construct the same by moulding the insulating screw 20 of bakelite, or insulation having similar properties, with the screw thread moulded therein.

Extending from the bottom of the pocket 19 is a smaller bore 21, adapted to receive an electrical conductor, and in the case of uninsulated wire, the bore 21 may be extended from the pocket 19 to the exterior of the insulating body 16. I prefer, however, to use insulated wire with my connector, and for this reason the exterior end of the bore 21 is enlarged as at 22, or provided with a counterbore 22. In the construction of connectors of small size I contemplate moulding the insulating body 16 in finished conformation, with the exception of the small bore 21, which may be made by a single operation of drilling after moulding, but in the provision of connectors of larger size I contemplate moulding the insulating body 16 in complete and finished form.

The insulating screw 20 which is moulded of insulation, as previously described, is provided with a head 23, having a knurled periphery 24 to permit manual grip in screwing the screw 20 to clamping position. The exterior surface 25 of the head 23 may be also provided with indicia such as symbols for plus and minus, which may likewise be moulded therein, and the depressions filled with a paint or other coating of a color opposite to that of the insulating body 16 and the head 23.

In further constructing my connector, I insert the stripped end of an insulated wire 26 in the bore 21 with the insulation 27 fitting into and filling the counterbore 22. The stripped end of the wire 26 should pref-

erably be of a length extending from a bore 21, when in assembled relation, into the threaded pocket 19. Although any type of wire may be used with my connector, such as single strand wire, insulated or uninsulated, or stranded wire, insulated or uninsulated, braided or twisted, I prefer to use insulated stranded wire, and within the threaded pocket 19 I splay or spread out the strands of the wire 26 as at 27, in order to provide a better bond and contact, as will be further described.

I next fill the threaded pocket 19 by fusing lead or some other non-corroding metal into the pocket, permitting the same to run into the pocket 19 about the splayed end 27 of the wire 26, intimately soldering the fused metal with the end of the wire 26, and filling and overflowing the pocket 19, covering the adjacent side of the cross bore 17.

The use of a non-corroding metal for the plug 31 of my connector, as well as an insulating casing or clamping support of non-corroding material, is a very important feature of my invention as with the connectors of the prior art the sulphuric acid and fumes therefrom quickly corrode the connectors at the point of contact and other points, increasing the contact resistance and rendering disconnection difficult. However, my insulating casing may also be used with plugs of other metals to make connectors which are insulated in a manner not accomplished by any of the devices of the prior art.

The cross bore 17 may then have its side 28, which is composed preferably of lead or other non-corroding metal, shaped by filing or by the use of other cutting tools, to a substantially circular shape at the base 29, with preferably sloping walls 30, extending from said circular portion. The conformation of the finished aperture 17 may be made so as to accurately fit the terminal posts 13 and 14, if desired, but I prefer to form the wall 28 as shown with a circular central portion and substantially straight sloping sides 20, in order to secure a maximum of contact with the majority of the conductors of various sizes, and a curved contact with terminals of the size adapted to fit the curved portion 29. The rough portions of the plug 31 extending from the aperture 17 may then be trimmed off flush with the external surface of the insulating body 16, by filing, grinding, cutting, or the like.

Another method of forming the plug 31 which is the preferred method, is as follows: After the insulating non-corroding casing has been constructed, as previously described, the screw 20 having been removed from the bore 18, a moulding core 33 of suitable material may be provided of such size and shape to fill that portion of the aper-

ture 17 adjacent the bore 18. The shape of the core 33 should be such that it will fill the aperture 17 and form the exposed surface 29 of the plug 31 to the conformation shown in Figure 3. This core should also have a projecting apron 34 which will fit the lower side of the casing 15 so that when the moulding core is placed in vertical position or at a slight tilt for a purpose to be further described, the casing 16 may be placed thereon with the moulding core in the aperture 17 and filling the right hand part thereof.

The apron 34 previously mentioned should then close the lower part of the remainder of the aperture 17, forming a cup open at the top consisting of the pocket 19 and part of the aperture 17 and the wire 26 with its splayed end 27 having been previously arranged in the casing, the lead or other non-corroding metal, may be poured in the said cup filling the same to form the plug 31 previously described. In order to cause the lead to run down into pocket 19 that end of the casing may be tilted downward if desired, or air pressure may be applied to the upper surface of the lead in the cup to force the lead into place in the manner used for casting dental inlays, as far as applicable.

The plug 31 may thus be moulded with a minimum of machining, having a surface 29 of any shape desired, the preferred form being described above. It should be noted that the moulding core 33 may be made to form the surface 29 exactly to fit any terminal plug but the moulding core 33 used need not necessarily be the same size as the terminal.

It will thus be observed that my connector, besides being particularly adapted to provide a maximum area of contact with one size of terminal, will also provide double lines of contact with terminals of larger size or a single line of contact with terminals of smaller size. Furthermore, the soft metal plug 31 is peculiarly adapted to shape its own surface in a measure to the surface of the contact terminal with which it engages.

In the use of my connector, the external terminal, or other conductor to be connected, is inserted in the aperture 17, and the screw 20 is brought to bear upon the said conductor by turning the head 24 in the usual manner, the screw advancing in the bore 18 and clamping the conductor 14 against the non-corroding metal plug 31. However, I desire it to be understood that my connector may also be used with or without the wire 26 for connecting a plurality of conductors together by clamping them all within the aperture 17, thereby establishing connection between the conductors so clamped, and also between the said conductors and the conducting plug 31.

I also desire it to be understood that my connector may be used without the clamping screw 20 by using an aperture 17 adapted to fit closely upon the tapering terminal 5 post so that the terminal post 14 would be in effect, wedged into the aperture 17 with the post 14 in contact with the plug 31. The external shape of the insulating body 16 may be of any desired conformation 10 adapted to have sufficient strength to support the parts previously described, but I prefer to make the insulating body 16 of substantially cylindrical shape, which may be tapered to a smaller size about the wire 26, 15 and the insulation 32, thereby providing a connector of small size and convenient shape. The screw head 23 should be of substantial size in order to permit a firm manual grip.

I further desire it to be understood that 20 the metal plug 31 may also be constructed of a shaped metal piece which is previously secured to the end of the insulated wire 27, and which may be constructed by moulding the insulating body 16 about the wire 26 and 25 metal plug 31 in such manner that these parts are moulded into place within the insulation, but in such case the plug 31 must be of a metal of a higher melting point than lead.

30 By constructing the frame or body of my connector of insulation, together with the clamping screw also of insulation and the plug 31 of lead, I have provided a connector which does not corrode as is the case with 35 the connectors of the prior art. Furthermore, my connector is fully and adequately insulated and may be grasped by the hands while in use without danger of shock or short circuit. It will also be observed that 40 I have provided a novel method consisting of a series of steps for the making of such a connector.

While I have shown and described a specific embodiment of my invention, it will be 45 understood that many modifications thereof may be made without departing from the spirit of the invention, and I do not desire to be limited to the precise details of construction set forth, but desire to avail myself 50 of all changes within the scope of the appended claims.

Having thus described my invention, what I claim as new and desire to secure by Letters Patent of the United States is as follows:

1. In an electrical connector, a non-corrod़ing body portion, having an opening therewith, a threaded bore communicating therewith and providing a pocket below said opening, and a smaller bore leading from said pocket out of said body, an electrical conductor extending from said smaller bore into said pocket, and a non-corrod़ing screw for clamping other conductors in contact 65 with said first named conductor.

2. In an electrical connector, a moulded insulating body portion having a recess therein and a threaded bore communicating with said recess and providing a pocket below said recess, a soft metallic plug fused 70 into said pocket, filling the same and providing a wall for said recess, and a moulded insulating screw for clamping conductors in contact with said plug.

3. In an electrical connector, a moulded insulating body having a recess therein, a pocket in the one side thereof, a smaller bore extending from said pocket and a counterbore from said smaller bore to the exterior of said body, an insulated conductor having its insulation within said counterbore, a stripped end of said conductor in said smaller bore, a splayed end of said conductor in said pocket, and a fused metallic plug connected with said end and filling said pocket. 75 80 85

4. In an electrical connector, a moulded insulating body having a recess therein, a threaded bore communicating with said recess and forming a pocket on the opposite side thereof, a smaller bore extending from said pocket and a counterbore from said smaller bore to the exterior of said body, an insulated conductor having its insulation within said counterbore, a stripped end of said conductor in said smaller bore, a splayed end of said conductor in said pocket, a fused metallic plug connected with said end and filling said pocket, and an insulating screw for clamping conductors within said recess against said plug. 90 95 100

5. The method of making a connector comprising, moulding an insulating frame member with a recess therein and an intersecting threaded bore having a pocket below said recess, filling the said pocket by fusing 105 metal therein to form a wall for said recess, and moulding a threaded screw to fit said threaded bore.

6. The method of making a connector comprising, moulding an insulating frame member having a recess therein and an aperture therethrough transverse to said recess, communicating therewith and consisting of a threaded bore and pocket below said recess, and a smaller bore, introducing an electrical conductor through said smaller bore into said pocket, fusing metal about said conductor to fill said pocket and form a wall for said recess, and shaping said wall to conform to the shape of a terminal member. 110 115 120 125

7. The method of constructing a connector comprising, moulding an insulating frame member having an opening extending therethrough, a threaded bore extending past and intersecting said opening, and a smaller bore continuing said first bore through said frame, introducing a stranded wire into said threaded bore through said smaller bore, splaying said stranded wire in said threaded bore, and fusing metal about said 130

wire to fill said bore and form a wall for said opening.

8. The method of constructing a connector comprising, moulding an insulating frame member having an opening extending therethrough, a threaded bore extending past and intersecting said opening, and a smaller bore continuing said first bore through said frame, introducing a stranded wire into said threaded bore through said smaller bore, splaying said stranded wire in said threaded bore, and fusing metal about said wire, filling said bore up to and into said opening, and shaping said metal when hard to conform to the shape of a terminal conductor.

9. The method of constructing a connector comprising, moulding an insulating frame member having an opening extending therethrough, a threaded bore extending past and intersecting said opening, and a smaller bore continuing said first bore through said frame, introducing a stranded wire into said threaded bore through said smaller bore, splaying said stranded wire in said threaded bore, and fusing metal about said wire, filling said bore up to and into said opening, shaping said metal when hard to conform to the shape of a terminal con-

necter, and moulding an insulating screw to fit said threaded bore.

10. The method of constructing a connector comprising, moulding an insulating frame member having an opening extending therethrough, a threaded bore intersecting and extending past said opening, a smaller bore extending from said threaded bore, and a counterbore extending from said smaller bore through said frame, introducing the stripped end of an insulated stranded wire into said smaller bore, the insulation being received in said counterbore, splaying said stranded wire in said threaded bore and fusing metal about said wire to fill said threaded bore to form a wall for said opening.

11. The method of making a connector comprising, moulding an insulating frame member with a recess therein and an intersecting threaded bore having a pocket below said recess, filling the said pocket by fusing non-corroding metal therein to form a wall for said recess, and moulding a threaded screw to fit said threaded bore.

In witness whereof, I hereunto subscribe my name this 14th day of October, 1926.

CHARLES G. JANSKY.
